UNITED STATES PATENT OFFICE.

HARRY K. HEADLEY, OF EAST LIVERPOOL, OHIO.

POTTER'S TOOL.

SPECIFICATION forming part of Letters Patent No. 637,781, dated November 28, 1899.

Application filed February 20, 1899. Serial No. 706,089. (No model.)

To all whom it may concern:

Be it known that I, HARRY K. HEADLEY, a citizen of the United States, residing at East Liverpool, in the county of Columbiana and State of Ohio, have invented or discovered a new and useful Improvement in Potters' Tools, of which the following is a full, clear, and exact description, reference being had to the accompanying drawings, forming part of this specification, in which—

Figure 1 is a view in side elevation, showing the application of my improvement to a molding apparatus for earthenware. Fig. 2 is an enlarged detail view in side elevation of the tool-clamping device forming the subject-matter of my present invention. Fig. 3 is a cross-sectional view taken in the line III III of Fig. 2. Fig. 4 is a plan view thereof, partly in section, as indicated by the line IV IV of Fig. 2. Fig. 5 is a similar view indicated by the line V V of Fig. 2. Fig. 6 is a similar view on line VI VI of same figure. Fig. 7 is a detail perspective view of the clamping-yoke. Fig. 8 is a similar view of the adjusting or backing strip.

My invention relates to tool-clamps for molding-machines for shaping articles in earthenware; and it consists of a head adapted to be mounted in the machine and to receive and hold the shaping-tool in such a manner as to render it very efficient and exact in operation, easily and quickly removed, and to provide for rapid and accurate adjustment.

Referring now to the drawings, 2 represents the usual housing, within which is partially mounted the socket-arm 3, adapted to receive the shank 4 of the tool-clamp. At the outer end of such shank is the head 5, through which extends a longitudinal slot 6, between upper and lower horizontal body portions 7 8 of the head, joining which portions at the back is the connecting-bridge 9, forming a bearing for the clamping screw-bolt 10. The yoke 11 is provided with a vertical slotted opening 12, adapted to receive the tool 13, such opening being somewhat wider than the thickness of the tool, and between the integral back and front portions 14 15 and ends 16. At the middle portion the back is reinforced, as at 17, in which reinforcement is secured, preferably by casting therein, the clamping-bolt 10, threaded at its outer end, such reinforcement

being adapted to enter and have a lateral movement within a corresponding enlargement 18 in the head. While such reinforcement provides strengthening means for the portion of the yoke to which the bolt is secured, it will be understood that such construction is not absolutely necessary and may be dispensed with.

The front face 19 of the portion 8 of the head is somewhat recessed beyond the face of the upper portion 7 sufficient to admit of the insertion of the adjusting-plate 20, which is mounted on sliding pins 21, entering corresponding sockets in the lower member 8 and preferably riveted at the ends to prevent withdrawal, such pins being capable of sufficient movement longitudinally in the sockets to permit of the adjustment of plate 20. This plate is set outwardly by set-screws 22 to adjust it even with the face of member 7, or beyond the face of member 7 in case it is desired to set the tool at an angle.

The tool A is of the usual or any desired construction adapted to this class of work, being provided with a forming-templet or shaping edge a at its lower extremity, made to conform to the desired shape of one-half of the diametrical contour of the article to be made, as will be well understood by those skilled in the art to which this invention relates.

The tool A is set within the head and maintained as to its vertical position by two slotted links 23 23, to which the tool is clamped by a securing-bolt 24, passing through the tool and slots of the links, by which it is rigidly set with relation to such links and its elevation in the head regulated, as is usual with this class of tools. The head is provided with an abutment 25, against which one of the links bears to limit its movement and insure proper location when reinserting in the head after removal, the tool having been set properly with relation to the links. The head 5 is provided with an extended handle 26 of any desired length by which the head is raised and lowered upon the pivoted support 27 in the housing. Downward motion is limited by an adjustable bearing 28, adapted to contact with an extension 29 of the housing.

The tool having been inserted within the clamp, the tightening-bolt 10 is screwed up

by adjusting nut 30 against the head and plate 20, such plate having been set out to its proper position, as has been described, when the machine is ready for operation.

5. In removing the tool from the head the links are allowed to remain in position, so that when it is again desired to use the tool it may be inserted very quickly and accurately without additional adjustment.

10. 31 is the revolving wheel, upon which the ware is formed, being provided with any suitable or customary means for its rotation, as a belt-pulley 32.

15. The advantages of my invention will be appreciated by those skilled in the art to which it pertains, as it provides a much more rapid and accurate means for adjustment of the tool than the present practice, in which it is bodily secured to the head by retaining screw or bolts, entailing considerable time and care to make changes from one tool to another and requiring a separate adjustment at each operation. It is very simple and efficient, cheap and easy to construct and operate, and 25 not liable to get out of order. Changes and variations may be made in its details, form, or design by the skilled mechanic without departing from my invention, since I do not desire to be limited to the exact construction 30 shown in the drawings, but to include all such changes as embodied in the following claims.

Having described my invention, what I claim, and desire to secure by Letters Patent, is—

35. 1. A tool-holder for pottery-molding machines consisting of a head provided with a link-abutment on its upper face, upper and lower longitudinal bearing-faces, an intervening longitudinal cavity, a yoke mounted within the cavity provided with a longitudinal vertical tool-holding slot, a clamping screw-bolt secured to the yoke, a bearing therefor in the head, and an adjusting-nut for the clamping screw-bolt, substantially as set forth.

40. 2. A tool-holder consisting of a head provided with a stationary and an adjustable face respectively, an intervening longitudinal cavity, a yoke mounted within the cavity and means for adjusting the yoke toward the bearing-faces, substantially as set forth.

45. 3. A tool-holder consisting of a head provided with a stationary and an adjustable front face respectively, an intervening longitudinal cavity, a tool-clamping yoke within the cavity, an adjusting-bolt secured to the yoke and a tightening-nut adapted to engage the screw, substantially as set forth.

50. 4. A tool-holder consisting of a head provided with a stationary front bearing-face, an adjustable plate mounted on pins, set-screws mounted in the head for adjusting the plate outwardly, an intervening longitudinal cavity, a tool-clamping yoke mounted in the cavity and capable of movement therein, an adjusting-bolt secured to the yoke and passing

55. 65. backwardly through a bearing in the head

and a tightening-nut adapted to engage the screw, substantially as set forth.

5. In a pottery-molding machine, the combination of a tool-holder consisting of a head provided with a link-abutment on its upper face, upper and lower longitudinal bearing-faces, an intervening longitudinal cavity, a yoke mounted within the cavity provided with a longitudinal vertical tool-holding slot, a clamping screw-bolt secured to the yoke, a bearing therefor in the head, an adjusting-nut for the clamping-bolt, a tool engaged by the clamp, and supporting-links adjustably secured to the tool and bearing upon the upper face of the head, substantially as set forth.

6. In combination with a housing provided with a tilting socket: a tool-holder consisting of a head provided with upper and lower longitudinal bearing-faces, an intervening longitudinal cavity, a yoke mounted within the cavity provided with a longitudinal vertical tool-holding slot, a clamping screw-bolt secured to the yoke, a bearing therefor in the head, and an adjusting-nut, substantially as set forth.

7. In combination with a housing provided with a tilting socket: a tool-holder consisting of a head provided with upper and lower longitudinal bearing-faces, an intervening longitudinal cavity, a yoke mounted within the cavity provided with a longitudinal vertical tool-holding slot, a clamping screw-bolt secured to the yoke, a bearing therefor in the head, an adjusting-nut for the bolt, and a shank extending from the head and adapted to be inserted in the tilting socket, substantially as set forth.

8. In combination with a housing provided with a tilting socket: a tool-holder consisting of a head provided with upper and lower longitudinal bearing-faces, an intervening longitudinal cavity, a yoke mounted within the cavity provided with a longitudinal vertical tool-holding slot, a clamping screw-bolt secured to the yoke, a bearing therefor in the head, an adjusting-nut for the bolt, a shank extending from the head and adapted to be inserted in the tilting socket, and an oppositely-extending operating-handle, substantially as set forth.

9. In combination with a potter's tool provided with supporting devices and means for adjustably securing such devices to the tool: a tool-holder consisting of a head upon which the supporting devices are adapted to rest and having faces against which the tool is adapted to bear, and provided with an adjustable yoke adapted to clamp the tool against such faces, substantially as set forth.

In testimony whereof I have hereunto set my hand.

HARRY K. HEADLEY.
